LOUDSPEAKER SYSTEM

Donald R. Hall, Oakland, and Ernest G. Danielson, San Francisco, Calif., assignors to Remler Company, Ltd., San Francisco, Calif., a corporation of California

Application February 23, 1937, Serial No. 127,030

5 Claims. (Cl. 179—1)

This invention relates generally to loud speaker systems of the type in which one or more remote loud speaker units are connected to a central amplifier system.

In certain loud speaker systems, maintenance of the individual loud speaker units in proper operating condition is of prime importance. For example this is true of marine installations, where the individual loud speakers may be distributed over different parts of the ship, and where wiring for connecting the loud speakers to the central system is subject to accidental damage. The present invention has for its object the provision of indicating means which will at all times indicate either open or short-circuited conditions of the wiring, so that an operator may determine whether or not a particular speaker is operating properly.

Another object of the invention is to provide an indicator arrangement for a loud speaker system, which will make use of an indicator lamp of the filament type, together with an exciting current that is superposed upon the same circuit which carries the voice currents to the loud speaker unit.

Further objects of the invention will appear from the following description in which the preferred embodiments of the invention have been set forth in detail in conjunction with the accompanying drawing.

Referring to the drawing:

Fig. 1 is a circuit diagram, illustrating one form of the invention.

Fig. 2 is likewise a circuit diagram, illustrating a modification of the invention.

Fig. 3 is a circuit diagram, illustrating a further modification applicable to a plurality of loud speaker units.

Fig. 4 is a diagrammatic circuit layout, showing a complete loud speaker system.

Referring first to Fig. 1, I have shown a power amplifier 10 of the electron relay type, which forms a part of an amplifier system. In this instance the amplifier is of the push-pull type, making use of two amplifier tubes, together with a plate circuit transformer 11. The input of amplifier 10 connects to some source of voice currents, such as the output of a voltage amplifier, which in turn has its input connected to a microphone circuit. The loud speaker unit 12 includes a conventional voice coil 13, which is shown connected to the secondary of transformer 14.

Ordinarily the primary of transformer 14 would be directly connected to the secondary of transformer 11, by a simple link circuit including

the extended conductor lines L₁ and L₂. However if these lines should become open-circuited or short-circuited, the loud speaker unit 12 would fail to operate, but this condition would not be indicated in any way to the operator located at 5 the amplifier end of the circuit.

To afford indicating means I make use of a small indicator lamp 16 of the filament type, which in this instance is connected in series with conductor L₁, as illustrated. Also in series with 10 the circuit there is a source of exciting current which in this instance is represented by a battery 17. In order to maintain the system in operative condition in the event the filament of lamp 16 becomes open-circuited, the lamp is 15 shown shunted by a resistor 18, which has a value of resistance relatively high compared to the resistance of the lamp.

It will be apparent that the current flow from the battery 17 is determined mainly by the resistance of the connecting lines L₁ and L₂, the resistance values of the secondary winding of transformer 11, the primary of transformer 14, and the combined resistance of resistor 18 in shunt with lamp 16. The voltage of battery 17 25 is adjusted so that the lamp 16 is normally burned at somewhat less than full brilliancy. If lines L₁ and L₂ become open-circuited, current supply from the battery 17 will be interrupted, and the lamp 16 will be extinguished. If lines L₁ and L₂ become short-circuited considerable resistance, including that of the primary winding 30 of transformer 14, is removed, and lamp 16 is burned at a noticeably greater brilliancy. Such indications will be had irrespective of use of the 35 amplifier, with the exception however that when the amplifier is in use and lines L₁ and L₂ are conducting voice currents, there will be some variation in the illumination of lamp 16.

In the modification of the invention shown in Fig. 2, a shunt arrangement is provided for the indicating lamp 16, in place of the series arrangement of Fig. 1. Thus in this case the lamp 16 is connected in series with a choke inductance 21, the direct current resistance component of which 40 is relatively low, but which has relatively high reactance to voice frequencies. A resistor 22 is connected in series with the secondary of transformer 11, and the transformer secondary plus the resistor 22, is connected in shunt with the 45 serially connected lamp 16 and choke 21. Resistor 22 serves to minimize flow of current from the battery 17 through the secondary of transformer 11, thus serving to cause a major part of the current to flow through conductor lines L₁ 50 55

and L_2 and the primary of transformer 14 , to illuminate the lamp 16 . It will be apparent that with this arrangement any open circuit in lines L_1 and L_2 will cause current flow through lamp 16 to be interrupted, with the result that lamp 16 is extinguished. Short-circuiting of lines L_1 and L_2 causes a materially greater current flow through lamp 16 , thus causing the lamp to burn at greater than normal brilliancy.

10 Fig. 3 illustrates a system substantially the same as that described with respect to Fig. 2, except that in this instance a plurality of loud speaker units $12a$, $12b$ and $12c$, are connected to a common amplifier 10 . It will be noted that 15 signal lamps $16a$, $16b$ and $16c$ are provided for each of the loud speaker units, and that each signal lamp is also associated with an individual resistor $22a$, $22b$ and $22c$, which correspond to the resistor 22 of Fig. 2. In such a system there 20 will be a continuous indication, making it possible to immediately note an open-circuited or short-circuited condition of any one of the circuits leading to the loud speaker units, and to determine which one of the loud speaker units is 25 operative.

Fig. 4 illustrates a complete system making use of an indicator arrangement similar to Fig. 1, but with a plurality of loud speaker units. A microphone or microphone circuit is represented 30 at 8 , and connects to a driver or potential amplifier 9 . The output of the driver amplifier connects with the separate power amplifiers $10a$ to $10d$ inclusive, each of which connects to its individual loud speaker unit, by an arrangement such 35 as shown in Fig. 1. The arrangement of Fig. 4 has some advantages over the system of Fig. 3, in that failure of any one power amplifier will cause failure of only one loud speaker unit, whereas failure of the power amplifier 10 in Fig. 3, will make the entire system inoperative.

40 We claim:

1. In a loud speaker system making use of a power amplifier of voice currents having a plate transformer and also making use of a remote 45 loud speaker unit, the loud speaker unit including a voice coil and a transformer having both sides of its secondary connected to the voice coil, a circuit serving to link the output of the amplifier to said loudspeaker unit, the circuit including the secondary of the amplifier transformer and also 50 including a pair of conductor lines extending from the amplifier to the primary of the loudspeaker transformer, a source of direct current located at the amplifier end of the circuit and connected in series with the conductor lines to 55 impose a direct current component upon said circuit, said direct current component being isolated from the secondary of the loudspeaker transformer, and an indicating lamp likewise connected to said circuit at the amplifier end of 60 the same, and serving to indicate direct current flow through the conductor lines.

2. In a loud speaker system making use of a power amplifier of voice currents having a plate transformer, and also making use of a remote 65 loud speaker unit, a circuit serving to link the output of the amplifier to said loud speaker unit, said circuit including the secondary winding of said transformer and also including a pair of conductor lines extending from the amplifier to the 70 speaker unit, a source of energizing current connected in series with the secondary of said transformer and also with said conductor lines, an indicator lamp of the filament type connected in 75 series with the secondary of said transformer at

the amplifier end of said circuit, and a resistance shunting said lamp, said lamp being illuminated at a predetermined intermediate brilliancy during normal operation of the system, and being extinguished in the event the conductor lines are 5 open-circuited, and burned at a greater brilliancy than said conductor lines are short-circuited.

3. In a loud speaker system making use of a power amplifier of voice currents having an output transformer, and also making use of a remote 10 loud speaker unit, a circuit serving to link the output of the amplifier to said loud speaker unit, said circuit including a pair of conductor lines connected at the amplifier end to the secondary 15 of said transformer and connected at the loud speaker end to electrical elements of a loud speaker unit having both reactance and resistance components, a source of current connected to the circuit at the amplifier end of the same 20 and in series with both the secondary of the transformer and with said conductor line, a resistance connected in series with the secondary of said output transformer, a choke inductance having relatively low value of resistance and a 25 relatively high reactance to voice currents, an indicator lamp of the filament type connected in series with said choke, said lamp and said choke being connected in shunt with the secondary of the output transformer and said resistance, 30 whereby said lamp serves to indicate both open-circuited or closed-circuited conditions of said conductor line.

4. In a loud speaker system of the character described making use of a power amplifier of 35 voice currents having a plate transformer, and also making use of a remote loud speaker unit including a voice coil and a transformer having its secondary connected to the voice coil, a conductive circuit serving to link the output of the 40 amplifier to said loud speaker unit, said circuit including a pair of conductor lines extending from the amplifier to the speaker unit, the amplifier end of the conductor lines being connected to the secondary of the amplifier transformer and 45 the loud speaker ends of the conductor lines being connected to the primary of the loud speaker unit transformer, a source of current serially connected with said circuit at the amplifier end of the same, and indicating means associated with 50 the amplifier end of said circuit and serving to indicate either short-circuited or open-circuited condition of said conductor line, said indicating means including a signal lamp of the filament type.

5. In a loudspeaker system of the character described, making use of a power amplifier of voice currents having a plate transformer and also making use of a plurality of remote loud speaker units, each including a voice coil, and a 60 transformer having its secondary connected to the voice coil, a plurality of circuits serving to link the output of the amplifier to said loudspeaker unit, said circuits including a plurality of conductor lines connected to the secondary 65 of the amplifier transformer, the loud-speaker ends of the conductor lines being connected to the primaries of the loudspeaker transformers, thereby forming a plurality of separate current distribution circuits all connected to the secondary of the amplifier transformer, a source of direct current serially connected with one side of the secondary of the amplifier transformer, whereby direct current components are imposed upon all of said circuits, a plurality of signal 7

5 lamps of the filament type located at the amplifier end of said conductor, a plurality of choke inductances each having a relatively low value of resistance and a relatively high reactance to voice currents, each of said chokes being serially connected with an associated filament lamp, a plurality of resistors connected in series with the other side of said amplifier transformer second-

ary and said distribution circuit, each lamp and its associated choke being connected in shunt across the secondary of the amplifier transformer and said resistances, whereby each lamp serves to indicate both open circuited or closed circuited conditions of its associated distributing circuit.
